• 61,152.

Specification for Design.

Patented July 4, 1922.

Application filed January 10, 1922. Serial No. 158. Term of patent 7 years.

To all whom it may concern:

Be it known that I, WILLIAM DOWLING, a subject of the King of Great Britain, residing at New York, in the county of New York and State of New York, have invented a new, original, and ornamental Design for a Textile Fabric, of which the following is a specification, reference being had to the accompanying drawings, forming a part thereof.

The figure is a plan view of a section of the fabric embodying the design.

I claim:

The ornamental design for a textile fabric, as shown.

WILLIAM DOWLING.
